corporation of Michigan

No Drawing. Application February 27, 1932
Serial No. 595,650

20 Claims. (Cl. 260—116)

The present invention concerns an improved method of oxidizing alcohols, particularly mono-hydric aliphatic alcohols, with caustic alkali to produce aliphatic acids.

It has long been known that an aliphatic alcohol containing more than six carbon atoms may be reacted with solid sodium or potassium hydroxide at a temperature between about 240° and about 250° C. to form an alkali metal salt of the corresponding aliphatic acid in satisfactory yield, based on the quantity of alcohol reacted. Guerbet, Bull. Soc. Chem. (4) 11, 164—9 (1912), for instance, reacted each of a series of aliphatic and substituted aliphatic alcohols (each alcohol containing more than six carbon atoms) with approximately three times its chemical equivalent of solid potassium hydroxide in a sealed tube, at a temperature between 240° and 250° C. and during a 16 hour period, whereby he obtained the potassium salt of the corresponding acid in a yield of 95 per cent of theoretical, or higher, based on the quantity of alcohol reacted. While the method employed by Guerbet produces the desired acid in excellent yield based on the quantity of alcohol reacted, it necessitates long heating in the presence of a large excess of caustic alkali from which the desired reaction product must subsequently be separated, so that the process is time consuming, costly to operate, and the yields are low when based on the quantity of caustic alkali employed. The method employed by Guerbet is still further disadvantageous, when applied to the production of acids from alcohols containing less than seven carbon atoms, in that, during the oxidation of said alcohols by the caustic alkali, considerable quantities of the organic reactants are converted to olefines and resinous by-products.

We have now found that a primary mono-hydric aliphatic alcohol containing more than two carbon atoms may, in general, be reacted with a fused mixture of sodium and potassium hydroxides, at a temperature between about 250° and about 300° C., to form an alkali metal salt of an aliphatic acid in comparatively good yield, based both upon the quantity of alcohol reacted and upon the quantity of alkali metal hydroxide employed. We have found, furthermore, that when primary monohydric aliphatic alcohols, containing more than two and less than seven carbon atoms, are reacted with a fused alkali metal hydroxide mixture, according to our improved method, occurrence of the previously reported undesirable side reactions, such as the formation of saturated hydrocarbons, olefines,

resinous by-products, carbonates, etc., is substantially prevented. We have found, still further, that by operating according to the present method, the desired reaction may be substantially completed in a relatively short time as compared with the time required when operating according to methods previously known. In addition to the foregoing advantages, we have found that by operating according to our preferred method, hereinafter described, the desired free aliphatic acid product may be practically completely separated from the reaction mixture in nearly pure form and as the substantially anhydrous compound.

To the accomplishment of the foregoing and related ends, the present invention, then, consists of the method hereinafter fully described and particularly pointed out in the claims, the following description setting forth in detail several modes of carrying out the invention, such disclosed modes illustrating, however, but several of the various ways in which the principle of our invention may be used.

A mixture of sodium and potassium hydroxides in respective quantities between the ratios of about

1NaOH
2KOH

and about

3NaOH
1KOH

is heated to fusion in a suitable closed reactor provided with a mechanical stirrer, an inlet for alcohol, and an outlet for gaseous products. The fused alkaline mixture is stirred vigorously and the desired quantity of a primary aliphatic alcohol is gradually contacted therewith, the reaction mixture being maintained at a temperature between about 250° and about 300° C. (preferably between about 285° and about 295° C.) during the course of the reaction. The introduction of alcohol to the reaction mixture is continued, preferably, until from about 85 to about 95 per cent of the caustic alkali initially employed is reacted.

Under optimum operating conditions substantially all of the alcohol employed may be reacted directly with the fused alkali metal hydroxide, but ordinarily a portion of the alcohol admitted to the reactor passes through the same unreacted. The unreacted alcohol may be condensed from its admixture with hydrogen, which is generated during the reaction, and returned to the reactor.

After the desired quantity of alcohol is reacted, we have found that the reaction mixture may, in

some instances, contain a relatively small quantity of unreacted alcohol. This alcohol, if permitted to remain in the mixture, may esterify a portion of the aliphatic acid product during the 5 steps of separating the latter as the free compound. In such case the product will be contaminated somewhat by the presence of the ester formed. In order to avoid such contamination and at the same time obtain the product in anhydrous form, we have found that the heated and stirred reaction mixture may advantageously be treated with an aqueous solution of an aliphatic acid (corresponding to that formed through oxidation of the alcohol used) in quantity sufficient 10 to substantially neutralize the mixture. During the course of such neutralization, the water added is vaporized, and effectively steam distills all unreacted alcohol from the mixture. Heating of the fused mixture is continued until practically 15 all water is vaporized therefrom. The mixture is then cooled to solidification, pulverized, acidified with a strong mineral acid, such as gaseous hydrogen chloride or concentrated sulphuric acid (preferably the latter), and the aliphatic acid is 20 distilled from the acidified mixture. When sulphuric acid is employed to acidify the neutralized reaction mixture, the latter should be cooled to a temperature sufficiently low so that components thereof will not be oxidized by sulphuric acid, 25 prior to adding said acid thereto.

We have found the above described method of recovery to be advantageous in separating an aliphatic acid from an alkaline mixture containing salts of the same, in that by means of such method 30 practically all of the aliphatic acid in the reaction mixture may be separated directly, in nearly pure form, and as the substantially anhydrous compound. The aliphatic acid product may, however, be separated from the previously described reaction mass in any of the usual ways, e. g. by direct 35 acidification of the cooled alkaline reaction mixture with a strong mineral acid and distillation of the aliphatic acid product from the acidified mass. The latter method is disadvantageous over 40 our preferred method in that the aliphatic acid thereby separated generally contains an appreciable quantity of water which, frequently, may be removed from the product only with extreme difficulty.

45 Through operating according to our preferred procedure, a primary monohydric aliphatic alcohol may be oxidized to form an alkali metal salt of the corresponding aliphatic acid in relatively high yield, based on both the quantity of alcohol reacted and on the quantity of alkali metal 50 hydroxide employed; undesirable side reactions, such as the formation of saturated hydrocarbons, olefines, carbonates, etc., are practically avoided; and a substantially anhydrous aliphatic acid is separated from the reaction mixture in 55

60 excellent yield and as the practically pure compound.

65 When normal propyl alcohol is reacted with a fused mixture of sodium and potassium hydroxides according to our improved method, propionic acid may be recovered from the reacted mass through procedure similar to that previously described. If desired, however, the reacted mixture may be dissolved in aqueous sodium hydroxide and sodium propionate be crystallized from the resultant solution. The mother liquor 70 may be evaporated to dryness, and the residue, which will consist of potassium hydroxide and residual sodium hydroxide and alkali metal propionate, may be returned to the initial reaction 75 wherein it may be employed for the oxidation of additional quantities of alcohol.

80 As previously stated, any primary monohydric aliphatic alcohol containing more than 2 carbon atoms may be oxidized according to the method herein described and an alkali metal salt of the corresponding aliphatic acid be formed in excellent yield. In the case of ethyl alcohol, however, a considerable portion of the alcohol is decomposed to form ethylene, so that for the successful 85 oxidation of ethyl alcohol with fused caustic alkali, special precautions are required, which are particularly described and claimed in our pending application Serial No. 593,086, filed February 15, 1932.

90 In the accompanying table of examples are 95 described the results obtained when various monohydric aliphatic alcohols were oxidized according to our improved method. In each of the runs described, a substantially anhydrous mixture of sodium and potassium hydroxides in the 100 respective quantities shown was placed in an enclosed iron reactor provided with a mechanical stirrer, an inlet for alcohol and an outlet for gaseous products, e. g. hydrogen. The alkali 105 metal hydroxide mixture was heated to fusion and maintained at the temperature indicated, with stirring, while the desired alcohol was gradually contacted therewith. During the course 110 of the reaction hydrogen, which was evolved from the stirred mixture, was conducted from the reactor through a condenser wherein any alcohol which had passed through the reactor unreacted was condensed as a liquid. The unreacted alcohol was weighed and the difference between the quantity of alcohol employed and the quantity recovered as unreacted material was 115 the quantity of alcohol reacted. The quantities of alcohol shown in the table are the quantities 120 calculated as having been reacted.

125 After the reaction was substantially completed, the reaction mixture was cooled, dissolved in water and the respective quantities of alkali metal hydroxide, carbonate, and aliphatic acid prod-

ucts present were determined through analysis of aliquot portions of the resultant solution.

In the examples, it will be noted that the desired aliphatic acid was in each instance formed in a yield of 93 per cent of theoretical or higher, based on the quantity of alcohol reacted. In runs 1, 3, and 4 more than 88 per cent of the alkali metal hydroxide employed was reacted to form the desired alkali metal salt of the aliphatic acid. In runs 1, 3, and 4 the alkali metal salt of the aliphatic acid was formed in a yield greater than 80 per cent of theoretical, based on the quantity of alkali metal hydroxide employed, and greater than 90 per cent of theoretical based on the quantity of alkali metal hydroxide reacted. Runs 2 and 5 were made for the purpose of determining the possible yield of acid based on the quantity of alcohol reacted. In each of the last mentioned runs, the reaction was still progressing rapidly when the addition of alcohol was discontinued.

The principle of our invention may be practiced in ways other than those previously described. The higher primary monohydric aliphatic alcohols, such as n-octyl alcohol, n-nonyl alcohol, 25 cetyl alcohol, etc., may for instance be reacted with a fused mixture of sodium and potassium hydroxides, according to our improved method, and the corresponding aliphatic acids be obtained in excellent yield.

30 We have previously stated that a fused caustic alkali mixture initially containing sodium and potassium hydroxides in a molecular ratio between about

40 may be employed as an agent for the oxidation of alcohols according to our method. When certain alcohols, e. g. some of the higher aliphatic alcohols, are to be oxidized according to the present method and mixtures of sodium and potassium hydroxides initially containing sodium hydroxide in a proportion appreciably greater than that represented by the molecular ratio

50 are employed as oxidizing agents, the reaction mixture may tend to become thick and difficult to stir as the reaction proceeds, and, indeed, may sometimes even solidify. If a reaction mixture becomes difficult to stir, it may be made more liquid by adding either the alkali metal hydroxide or the alkali metal salt of the aliphatic acid product required to shift the ratio of sodium and potassium compounds in the reaction mixture toward an equimolecular basis. We frequently find it advantageous, however, to avoid difficulties such as those last described, by employing a fused caustic alkali mixture which initially contains sodium and potassium hydroxides in respective amounts between the molecular ratios of about

and about

70 Although any reaction temperature between about 250° and about 300° C. may be employed in practicing our invention, we prefer to maintain the reaction mixture at a temperature between

about 285° and about 295° C. When the reaction temperature is maintained below about 285° C. the reaction may become sluggish so that the time required for substantially complete reaction is increased materially. When all of the reactants employed are substantially anhydrous and the temperature is increased materially above 300° C., the alkali metal salt of the aliphatic acid may decompose materially to form undesirable by-products such as carbonates.

80 The reactants employed in our improved process may contain a relatively small proportion of water, the presence of which, we have observed, tends to inhibit the decomposition and over oxidation of the desired products. If, for instance, the alcohol employed contains an appreciable quantity (2 to 8 per cent) of water, or if the fused alkaline mixture is substantially saturated with water under the reaction conditions maintained, the reaction temperature may be raised to about 85 325° C. without material decomposition or over oxidation of the product occurring. Apparently water tends to prevent undesirable side reactions but at the same time tends to slow up the principal reaction. The presence of a relatively small 90 quantity of water in the reaction mixture, therefore, may at times be highly desirable, although the presence of any considerable quantity (e. g. more than about 15 per cent in the fused alkaline mixture or more than about 8 per cent in the alcohol) should be avoided.

100 It is important to stir the fused reaction mixture vigorously during the addition of the alcohol, so as to expose unreacted hydroxide continually to contact with the alcohol. While the reaction 110 will occur under the operating conditions previously described, even though the mixture is not stirred, stirring maintains the mixture in a substantially homogeneous condition, prevents local overheating of the fused mixture and resultant 115 decomposition of the desired product, and, in general, aids in obtaining smooth reaction between the alcohol and the alkali.

120 The results shown in the table were obtained when the alcohols were reacted with the fused alkali metal hydroxide mixture under approximately atmospheric pressure. The reaction may in some instances, however, be carried out advantageously under increased pressure; particularly when the reactants contain an appreciable 125 quantity of water. If an alcohol containing about 5 per cent of water is to be oxidized, for instance, an increase in pressure aids in maintaining suitable contact between all reactants and not only shortens the time required for reaction at a given 130 temperature, but also aids in effecting substantially complete reaction. Generally, the pressure need not exceed about 4 atmospheres to assure smooth reaction.

135 Other modes of employing the principle of our invention may be employed instead of those explained, change being made as regards the method herein disclosed, provided the step or steps stated by any of the following claims or the equivalent of such stated step or steps be employed.

140 We therefore particularly point out and distinctly claim as our invention:

1. In a method of making an aliphatic acid, the step which consists in reacting a primary monohydric aliphatic alcohol, containing more than 145 two carbon atoms, with a fused mixture initially containing sodium and potassium hydroxides in a molecular ratio between about

150

and about

5 the fused mixture being maintained at a temperature between about 250° and about 325° C. during the course of the reaction.

10 2. In a method of making an aliphatic acid, the steps which consist in reacting a primary monohydric aliphatic alcohol, containing more than two carbon atoms with a fused mixture initially containing sodium and potassium hydroxides in a molecular ratio between about

and about

20 stirring the fused mixture and maintaining the same at a temperature between about 250° and about 300° C. during the course of the reaction.

25 3. In a method of making an aliphatic acid, the steps which consist in introducing a primary monohydric aliphatic alcohol, containing more than two carbon atoms, into contact with a fused mixture which initially contains sodium and potassium hydroxides in a molecular ratio between about

and about

35 stirring the fused reaction mixture and maintaining the same at a temperature between about 250° and about 300° C. during the course of the reaction, acidifying the reacted mixture with a strong mineral acid to liberate the free aliphatic acid product, and separating the latter from the acidified mass.

40 4. In a method of making an aliphatic acid, the steps which consist in introducing a primary monohydric aliphatic alcohol, containing more than two carbon atoms, into contact with a fused mixture which initially contains sodium and potassium hydroxides in a molecular ratio between about

and about

50 stirring the fused reaction mixture and maintaining the same at a temperature between about 250° and about 300° C. during the course of the reaction, condensing unreacted alcohol which is evolved during the reaction and returning the condensed alcohol to the reaction, substantially neutralizing the reacted mixture with the aliphatic acid corresponding to that formed through oxidation of the alcohol employed, heating the neutralized mixture to remove moisture therefrom, cooling to solidification, acidifying with a concentrated strong mineral acid, and distilling the aliphatic acid product from the acidified mass.

55 5. In a method of making an aliphatic acid, the steps which consist in reacting a primary monohydric aliphatic alcohol, containing more than two and less than seven carbon atoms, with a fused mixture initially containing sodium and po-

tassium hydroxides in a molecular ratio between about

and about

stirring the reaction mixture and maintaining the same at a temperature between about 250° and about 325° C. during the course of the reaction.

60 6. In a method of making an alkali metal salt of an aliphatic acid, the steps which consist in reacting a primary monohydric aliphatic alcohol, containing more than two and less than seven carbon atoms, with a fused mixture initially containing sodium and potassium hydroxides in a molecular ratio between about

and about

65 stirring the reaction mixture and maintaining the same at a temperature between about 250° and about 300° C. during the course of the reaction.

70 7. In a method of making an aliphatic acid, the steps which consist in introducing a primary monohydric aliphatic alcohol, containing more than two and less than seven carbon atoms, into contact with a fused mixture which initially contains sodium and potassium hydroxides in a molecular ratio between about

and about

75 stirring the fused reaction mixture and maintaining the same at a temperature between about 250° and about 300° C. during the course of the reaction, acidifying the reacted mixture with a strong mineral acid to liberate the free aliphatic acid product, and separating the latter from the acidified mass.

80 8. In a method of making an aliphatic acid, the steps which consist in introducing a primary monohydric aliphatic alcohol, containing more than two and less than seven carbon atoms, into contact with a fused mixture which initially contains sodium and potassium hydroxides in a molecular ratio between about

and about

85 stirring the fused reaction mixture and maintaining the same at a temperature between about 250° and about 300° C. during the course of the reaction, substantially neutralizing the reacted mixture with an aliphatic acid corresponding to that formed through oxidation of the alcohol employed, heating the neutralized mixture to remove substantially all moisture therefrom, cooling the mixture to solidification, acidifying with a concentrated strong mineral acid, and distilling the aliphatic acid product from the acidified mass.

90 9. In a method of making an aliphatic acid, the steps which consist in introducing a primary

monohydric aliphatic alcohol, containing more than two and less than seven carbon atoms, into contact with a fused mixture which initially contains sodium and potassium hydroxides in a molecular ratio between about

$\frac{1\text{NaOH}}{2\text{KOH}}$

and about

$\frac{3\text{NaOH}}{1\text{KOH}}$,

stirring the fused reaction mixture and maintaining the same at a temperature between about 250° and about 300° C. during the course of the reaction, condensing unreacted alcohol which is evolved during the reaction and returning the condensed alcohol to the reaction, substantially neutralizing the reacted mixture with the aliphatic acid corresponding to that formed through oxidation of the alcohol employed, heating the neutralized mixture to remove moisture therefrom, cooling to solidification, acidifying with a concentrated strong mineral acid, and distilling the aliphatic acid product from the acidified mass.

10. In a method of making an aliphatic acid, the steps which consist in introducing a primary monohydric aliphatic alcohol, containing more than two and less than seven carbon atoms, into contact with a fused mixture which initially contains sodium and potassium hydroxides in a molecular ratio between about

$\frac{1\text{NaOH}}{2\text{KOH}}$

and about

$\frac{1\text{NaOH}}{1\text{KOH}}$,

stirring the fused reaction mixture and maintaining the same at a temperature between about 250° and about 300° C. during the course of the reaction, condensing unreacted alcohol which is evolved during the reaction and returning the condensed alcohol to the reaction, substantially neutralizing the reacted mixture with an aqueous solution of the aliphatic acid corresponding to that formed through oxidation of the alcohol employed, heating the neutralized mixture to remove substantially all water and other volatile components therefrom, cooling to a temperature such that components thereof will not be appreciably oxidized by concentrated sulphuric acid, acidifying the mixture with concentrated sulphuric acid and distilling the aliphatic acid product from the acidified mass.

11. In a method of making an aliphatic acid, the steps which consist in neutralizing a fused alkaline mixture containing an alkali metal salt of said acid with an aqueous solution of the free aliphatic acid, heating the neutralized mixture to remove water and other volatile components therefrom, cooling to solidification, acidifying with a concentrated strong mineral acid and distilling the aliphatic acid product from the acidified mass.

12. In a method of making propionic acid the step which consists in reacting normal propyl alcohol with a fused mixture initially containing sodium and potassium hydroxides in a molecular ratio between about

$\frac{1\text{NaOH}}{2\text{KOH}}$

and about

$\frac{3\text{NaOH}}{1\text{KOH}}$,

the fused mixture being maintained at a temperature between about 250° and about 325° C. during the course of the reaction.

13. In a method of making propionic acid, the steps which consist in reacting normal propyl alcohol with a fused mixture initially containing sodium and potassium hydroxides in a molecular ratio between about

$\frac{1\text{NaOH}}{2\text{KOH}}$

and

$\frac{1\text{NaOH}}{1\text{KOH}}$,

stirring the fused mixture and maintaining the same at a temperature between about 250° and about 300° C. during the course of the reaction.

14. In a method of making propionic acid, the steps which consist in introducing normal propyl alcohol into contact with a fused mixture which initially contains sodium and potassium hydroxides in a molecular ratio between about

$\frac{1\text{NaOH}}{2\text{KOH}}$

and about

$\frac{3\text{NaOH}}{1\text{KOH}}$,

stirring the fused reaction mixture and maintaining the same at a temperature between about 250° and about 300° C. during the course of the reaction, substantially neutralizing the reacted mixture with propionic acid, heating the neutralized mixture to remove substantially all moisture therefrom, cooling the mixture to solidification, acidifying with a strong mineral acid and distilling propionic acid from the acidified mass.

15. In a method of making butyric acid, the step which consists in reacting normal butyl alcohol with a fused mixture initially containing sodium and potassium hydroxides in a molecular ratio between about

$\frac{1\text{NaOH}}{2\text{KOH}}$

and about

$\frac{3\text{NaOH}}{1\text{KOH}}$,

the fused mixture being maintained at a temperature between about 250° and about 325° C. during the course of the reaction.

16. In a method of making butyric acid, the steps which consist in reacting normal butyl alcohol with a fused mixture initially containing sodium and potassium hydroxides in a molecular ratio between about

$\frac{1\text{NaOH}}{2\text{KOH}}$

and

$\frac{1\text{NaOH}}{1\text{KOH}}$,

stirring the fused mixture and maintaining the same at a temperature between about 250° and about 300° C. during the course of the reaction.

17. In a method of making butyric acid, the steps which consist in introducing normal butyl alcohol into contact with a fused mixture which

initially contains sodium and potassium hydroxides in a molecular ratio between about

5 and about

- 10 stirring the fused reaction mixture and maintaining the same at a temperature between about 250° and about 300° C. during the course of the reaction, substantially neutralizing the reacted mixture with butyric acid, heating the neutralized mixture to remove substantially all moisture therefrom, cooling the mixture to solidification, acidifying with a strong mineral acid and distilling butyric acid from the acidified mass.

- 15 18. In a method of making isovaleric acid the step which consists in reacting iso-amyl alcohol with a fused mixture initially containing sodium and potassium hydroxides in a molecular ratio between about

25 and about

- 30 the fused mixture being maintained at a temperature between about 250° and about 325° C. during the course of the reaction.

- 35 19. In a method of making isovaleric acid, the steps which consist in reacting iso-amyl alcohol with a fused mixture initially containing sodium

and potassium hydroxides in a molecular ratio between about

5 and

80

stirring the fused mixture and maintaining the same at a temperature between about 250° and about 300° C. during the course of the reaction.

- 20 20. In a method of making isovaleric acid, the steps which consist in introducing iso-amyl alcohol into contact with a fused mixture which initially contains sodium and potassium hydroxides in a molecular ratio between about

25 and about

95

stirring the fused reaction mixture and maintaining the same at a temperature between about 250° and about 300° C. during the course of the reaction, substantially neutralizing the reacted mixture with isovaleric acid, heating the neutralized mixture to remove substantially all moisture therefrom, cooling the mixture to solidification, acidifying with a strong mineral acid and distilling isovaleric acid from the acidified mass.
